UNITED STATES PATENT OFFICE

THOMAS E. MURRAY, OF NEW YORK, N. Y.

ELECTRIC CUT-OUT.

No. 924,092.

Specification of Letters Patent. Patented June 8, 1909.

Application filed April 13, 1908. Serial No. 426,641.

To all whom it may concern:

Be it known that I, THOMAS E. MURRAY, a citizen of the United States, residing at New York, in the county of New York and 5 State of New York, have invented a certain new and useful Improvement in Electric Cut-Outs, of which the following is a specification.

The invention relates to electric cut-outs 10 or fuse boxes, and consists in the construction hereinafter set forth whereby a fuse plug (or plugs) combined with locking means prevents removal of the cover from the base portion of the device: also in the construction 15 whereby, after said cover is in place, access is prevented to the connections until said locking means are released and said plugs or plugs removed: also in the various combinations recited in the claims.

20 In the accompanying drawings—Figure 1 is a top view of my improved cut-out with the cover in place. Fig. 2 is a section on the line *x-x* of Fig. 1. Fig. 3 is a top view with the fuse plugs and cover removed. Fig. 4 is 25 an end view and Fig. 5 is a detailed view showing a locking bar 35 and ring 32.

Similar numbers and letters of reference indicate like parts.

The device as here shown is constructed to 30 receive the main supply wires of a three wire system and the terminals of two sets of house wires, connected to the mains on opposite sides thereof. The main wires are shown at A, B, C; one set of house wires at D, E, F; 35 and the other set of house wires at G, H, I. The neutral wires are respectively B, E, H.

The base portion 1 is preferably a block of porcelain and has three transverse grooves on its upper side to receive the main wires A, 40 B, C, and four cylindrical openings, each provided with a threaded metal lining or socket 2, 3, 4, 5. Communicating with the cylindrical openings and extending through the end walls of the base are openings 6, 7, 8, 9, 45 on the bottom of which and of the cylindrical openings are contact plates 10, 11, 12, 13. To these contact plates, by means of screws 14, are secured the ends of the wires D, F and G, I, and said contact plates also electrically connect respectively with the sockets 2, 3, 4, 5, as shown at 15, Fig. 2. In the bottom of each socket is a headed screw 16, the shank of which extends down through a plate 17 of insulating material and an opening 55 in the contact plate immediately below, and is received in a bar of metal which lies in

a recess formed in the under side of the base. One of these bars is shown at 18, Fig. 2. Another in dotted lines at 19, Fig. 3. The bar 18 has an upwardly bent portion 20 60 which enters an opening in the bottom of the groove receiving the main wire A. On the top of this bent portion is secured a metal clip 21 between the parts of which is held, by means of a fastening screw, an exposed portion of said wire A. The bar 19 has a similar upwardly bent portion entering an opening in the groove receiving the wire C and this wire in like manner is connected to said bent portion of bar 19 by a clip 22. By this construction, the main wire A is connected through bar 18 to the headed screws 16 at the bottom of sockets 2, 3, while the main wire C is connected through bar 19 to the similar headed screws 16 at the bottom of 75 sockets 4, 5. A third bar 23 lies in a groove on the under side of the base, between the grooves which receive bars 18 and 19, and has an elevated portion extending upward through an opening in said base to receive a 80 clip 24 similar to clips 21 and 22, by which is secured to it the neutral wire B. The ends of the bar 23 extend under openings 25 in the end walls of the base, and have connected to them by screws 26, Fig. 3, the terminals of 85 the neutral house wires E and H.

In each threaded socket 2, 3, 4, 5 is inserted a hollow cylindrical fuse plug J, K, L, M, preferably made of porcelain. Said plugs are detachably engaged to the base by 90 means of a threaded metal sleeve 27 on the exterior of each plug, constructed to enter the threaded socket 2, etc. Extending through the bottom of the plug is a contact plate 28. The fuse 29 is connected at its 95 lower end to the plate 28 and extends upwardly and through an opening in the wall of the plug, its upper extremity being connected to the exterior threaded sleeve 27. When a plug is seated in the base, the contact plate 28 meets the upper face of the headed screw 16 and in this way circuit is completed through the fuse. Thus, in Fig. 2, circuit proceeds from main wire A to bar 18, to screws 16 to contact plates 28, to 100 fuses 29 in plugs J, K, to sleeves 27, to contact plate 10 or 11 and so to house wire F or I. In similar manner the house wires D and G are connected through the fuses in plugs L, M, to main wire C.

Particular attention is now directed to the means for locking the fuse plugs in their

2
sockets, so that neither they nor the cover 31 of the device can be removed without tampering with a seal fastening. Integral with each cylindrical plug and on the upper part 5 thereof, is formed a shouldered ring 30, serrated or indented around its upper edge; the downwardly flanged cover 31 having openings in its flanges for the passage of the wires, and openings in its top for the fuse 10 plugs, is first put in place on the base 1. Before one plug J, M, of each pair is inserted through the openings in the top of the cover, and so into its socket, it is passed through a flat ring 32 of metal having two upward projections 33 in each of which projections, is a 15 vertical slot; so that ring 32 when the plug is finally seated, becomes clamped between the upper surface of the cover 31 and the shoulder of plug ring 30. A metal bar 35 having a shouldered enlargement 36 at one 20 end, is then inserted through the slots in the projections 33 until the shoulder of the enlargement 36 bears against the side of one of said projections. The lower edge of said bar 25 then lies in diametrically opposite indentations of the serrated top of the plug ring, and an end portion of said bar, preferably that nearest the said shoulder thereon, extends across the interval and enters an indentation 30 in the top ring of the next adjacent plug. Thus in Fig. 1 a bar 35 is seated in two indentations on top of plug J and extends across the interval and enters an indentation on top of plug L; and another bar 35 in like 35 manner is applied to plugs K and M. In the opposite end of each bar 35, is an opening to receive the shackle of any suitable seal fastening 37, (one, only, shown in Fig. 1), which is to be constructed in any known way 40 so that said shackle cannot be removed without destroying the seal, or otherwise leaving evidence of the fact of removal. It will be obvious that by reason of this construction, the fuse plugs cannot be rotated to withdraw, 45 them from their threaded sockets and so release the cover 31 because prevented by the locking bars 35, and that no locking bar can be withdrawn longitudinally from the indentations on top of the fuse plugs, because 50 prevented by its shouldered enlargement 36 and by the seal 37.

As shown in Figs. 1 and 4, when the cover 31 is in place, it completely prevents access to any of the exposed wires or to any connections between them, so that there is no way offered for unauthorized persons to insert ground or other connections in order improperly to take off current. The shouldered fuse plugs lock the cover in place, the bars 35 lock the fuse plugs, and the seals 37 prevent removal of the bars 35.

I claim:

1. In an electric cut out, a base having an internally threaded socket, a cover for said 65 base, a threaded fuse plug received in said

socket and passing through said cover and having a shoulder above and bearing on said cover, and a locking device positively engaging said plug for preventing rotation of said plug to remove the same from said socket. 70

2. In an electric cut out, a base, a cover therefor, a fuse plug seated in said base and passing through an opening in said cover and having a shoulder above and bearing on said cover, means on said fuse plug and in said 75 base whereby on the rotation of said plug in its seat, said plug is caused to engage with said base, and a locking device above said cover for preventing rotation of said plug to disengage the same from said base. 80

3. In an electric cut out, a base, a cover therefor, a fuse plug having an indentation on its upper surface, seated in said base and passing through an opening in said cover, means on said fuse plug and in said base 85 whereby on the rotation of said plug in its seat, said plug is caused to engage with said base, a locking bar entering said indentation, a holder for said bar, and means on said cover for engaging a protruding end of said bar to 90 prevent rotation of said plug to disengage the same from said base.

4. In an electric cut out, a base, a cover therefor, a cylindrical fuse plug having its upper end ring shaped and provided with a plurality of indentations, and the said plug being seated in said base and passing through an opening in said cover, means on said fuse plug and in said base whereby, on the rotation of said plug in its seat, said plug is 95 caused to engage with said base, a locking bar lying in diametrically opposite indentations in said ring, a holder for said bar, and means on said cover for engaging a protruding end of said bar to prevent rotation of said 100 plug to disengage the same from said base.

5. In an electric cut out, a base, a cover therefor, a cylindrical fuse plug having its upper end ring-shaped and shouldered, and provided with a plurality of indentations, 110 and the said plug being seated in said base and passing through an opening in said cover, means on said fuse plug and in said base, whereby, on the rotation of said plug in its seat, said plug is caused to engage with 115 said base, a ring interposed between said plug ring shoulder and said cover, upward projections on said ring having slots, a locking bar extending through said slots and lying in diametrically opposite indentations of 120 said plug, means on said cover for engaging a protruding end of said bar to prevent rotation of said plug, and means for preventing withdrawal of said bar longitudinally from said slots. 125

6. In an electric cut out, a base, a cover therefor, a cylindrical fuse plug having its upper end ring-shaped and shouldered, and provided with a plurality of indentations, and the said plug being seated in said base 130

and passing through an opening in said cover, means on said fuse plug and in said base, whereby, on the rotation of said plug in its seat, said plug is caused to engage with said 5 base, a ring interposed between said plug ring shoulder and said cover, upward projections on said ring having slots, a locking bar shouldered at one end to bear against one of said projections and extending through said 10 slots and lying in diametrically opposite indentations of said plug, means on said cover for engaging the end of said bar nearest to said shoulder thereon, and a seal fastening secured in an opening in the opposite end of 15 said bar.

7. In an electric cut out, a base of insulating material, circuit connections therein, a flanged cover of insulating material constructed to receive said base and to prevent 20 access to said circuit connections, two fuse plugs seated in and engaging said base and passing through openings in said cover, and means above said cover and engaging with both of said fuse plugs for preventing removal 25 from said base of said plugs and said cover.

8. In an electric cut out, a base, a cover therefor, two fuse plugs seated in said base and passing respectively through openings in 30 said cover, means on said fuse plugs and in said base, whereby on the rotation of said plugs in their seats, said plugs are caused to engage with said base, and a locking device connecting said plugs together for preventing the 35 rotation of said plugs to disengage the same from said base.

9. In an electric cut out, a base, a cover therefor, two fuse plugs seated in said base and passing respectively through openings in 40 said cover, means on said fuse plugs and in

said base, whereby on the rotation of said plugs in their seats, said plugs are caused to engage said base, and a locking bar above said cover and extending from plug to plug, and means for holding said bar to prevent 45 the rotation of said plugs in their seats.

10. In an electric cut out, a base, a cover therefor, two fuse plugs having indentations in their upper surfaces, seated in said base and passing respectively through openings in 50 said cover, means on said fuse plugs and in said base, whereby on the rotation of said plugs in their seats, said plugs are caused to engage with said base, a locking bar entering said indentations and extending from plug to 55 plug, a holder for said bar, and means for preventing removal of said bar from said holder.

11. In an electric cut out, a base having an internally threaded socket, a cylindrical externally threaded fuse plug entering said socket, and a locking device disposed outside of said base and positively engaging with said plug for preventing rotation of said plug to remove said plug from said socket. 60 65

12. In an electric cut out, a base having a socket, a fuse plug entering said socket, means operable by the rotation of said plug to cause said plug to engage with said base, and a locking device disposed outside of said 70 base and positively engaging with said plug for preventing rotation of said plug to remove said plug from said socket.

In testimony whereof I have affixed my signature in presence of two witnesses.

THOMAS E. MURRAY.
